Des. 186,730
Patented Nov. 24, 1959

186,730

SELF CONTAINED MOTION PICTURE EXHIBITOR AND VIEWING CABINET

Frank J. Urban, Louisville, Ky.

Application April 14, 1959, Serial No. 55,491

Term of patent 14 years

(Cl. D61—1)

Fig. 1 is a front perspective view of a self contained motion picture exhibitor and viewing cabinet, showing my new design;

Fig. 2 is a top plan view;

Fig. 3 is a side elevational view, the opposite side being substantially a mirror image thereof; and

Fig. 4 is a rear elevational view thereof.

I claim:

The ornamental design for a self contained motion picture exhibitor and viewing cabinet, as shown and described.
